Patented Dec. 23, 1919.

Inventor
B. Z. Matthews

By ~~John Murphy~~ Atty.

UNITED STATES PATENT OFFICE.

BURTCHAELL Z. MATTHEWS, OF LAKE BUTLER, FLORIDA, ASSIGNOR TO EDGAR N. MILLER, OF LAKE BUTLER, FLORIDA.

SUCTION-PIPE FITTING.

1,326,078.

Specification of Letters Patent. Patented Dec. 23, 1919.

Application filed May 31, 1919. Serial No. 300,833.

To all whom it may concern:

Be it known that I, BURTCHAELL Z. MATTHEWS, a citizen of the United States, residing at Lake Butler, in the county of Bradford and State of Florida, have invented certain new and useful Improvements in Suction-Pipe Fittings; and I do hereby declare the following to be a full, clear, and exact description of the invention, 10 such as will enable others skilled in the art to which it appertains to make and use the same.

This invention relates to suction pump attachments for wells and the primary object of the invention is to provide an improved means for connecting two pumps to a single well, whereby water may be had at two spaced points from the well.

Another object of the invention is to provide means for connecting a pair of suction pumps to a well, in such a manner, that either or both pumps can be operated without interfering with the operation of either pump.

A still further object of the invention is to provide an improved means for connecting a pair of vacuum pumps together, so that each pump will have a separate suction pipe, so that the operation of one pipe will not affect the operation of the other.

A still further object of the invention is to provide an improved device of the above character, which is durable and efficient in use, one that is simple and easy to manufacture, and one that can be placed upon the market at a reasonable cost.

With these and other objects in view, the invention consists in the novel construction, arrangement and formation of parts, as will be hereinafter more specifically described, claimed and illustrated in the accompanying drawings, forming a part thereof, in which:

Figure 1 is a side elevation of the improved device, and

Fig. 2 is a vertical section through the pipe fitting for connecting the pumps together.

Referring to the drawings in detail, 50 wherein similar reference characters designate corresponding parts throughout the several views, the numeral 1 generally indicates the improved device which includes the pipe fitting 2 having the suction pipes

3 and 4 of a pair of the ordinary or any preferred type of vacuum pumps. The pipe fitting 2 includes the T-shaped body 5 having the oppositely directed arms 6 and 7 and the downwardly extending legs 8. As shown, the arm 6 is smaller in diameter than the arm 7 and the arms are internally threaded so as to receive the threaded terminals of the suction pipes 3 and 4. The arm 6 is separated from the arm 7 and leg 8 by means of a central partition 10 and the lower wall of the same is provided with a relatively small threaded opening 11, which is in direct alignment with the bore of the leg 8. A relatively large suction pipe 12 is turned into the leg 8 and extends into the well below the water line thereof and receives the relatively small suction pipe 13 which has its upper end turned in the recess 11. Thus, it will be seen that the suction pipe 3 communicates with the relatively small suction pipe 13 and the suction pipe 4 communicates with the relatively large suction pipe 12, so that the pumps may be provided with the independent suction pipes which extend into the well and thus permit the independent operation of the pumps. The pipe 13 is also extended below the water line of the well and does not in any way whatsoever interfere with the action of the outer pipe 12. When the pump which has the suction pipe 4 is operated, the water which is drawn upwardly will pass around the inner pipe 13 and partition 10 and out of the arm 7 into the pipe 4.

From the foregoing description, it can be seen that an improved means is provided for connecting a pair of vacuum pumps together in such a manner that the pumps may be operated independently of each other or simultaneously.

In practice, I have found that the form of my invention illustrated in the accompanying drawings and referred to in the above description, as the preferred embodiment, is the most efficient and practical; yet realizing the conditions concurrent with the adoption of my device will necessarily vary, I desire to emphasize that various minor changes in details of construction, proportion and arrangement of parts may be resorted to, when required without sacrificing any of the advantages of my invention as set forth.

What I claim as new is:

1. In a device of the class described, a pair of independent pump suction pipes, a pipe fitting including outwardly extending arms and a downwardly extending leg, means for operatively connecting the arms to the pump suction pipes, a depending well suction pipe connected to the leg and communicating with one arm, a second well suction pipe arranged in the first mentioned suction pipe and communicating with the other arm, as and for the purpose specified.
- 10 2. In a device of the class described, the combination with the suction pipes of a pair of vacuum pumps, of a pipe fitting having a T-shaped body including a pair of out-

wardly extending arms and a downwardly extending leg, a partition dividing one arm from the other arm and leg, the suction pipes being secured to the arms and communicating therewith, a pipe secured to the leg and communicating with one of the suction pipes, and a second pipe arranged in the first pipe and secured to the partition and communicating with the other suction pipe, as and for the purpose specified. 20 25

In testimony whereof I affix my signature in presence of two witnesses.

BURTCHAELL Z. MATTHEWS.

Witnesses:

H. L. FOWLER.

Corrections in Letters Patent No. 1,326,078.

It is hereby certified that Letters Patent No. 1,326,078, granted December 23, 1919, upon the application of Burtchaell E. Matthews, of Lake Butler, Florida, for an improvement in "Suction-Pipe Fittings," were erroneously issued to Edgar N. Miller as assignee of the entire interest in said invention, whereas said Letters Patent should have been issued to *the inventor, said Matthews, and Edgar W. Miller*, said Miller being assignee of *one-half* interest only; the name of said assignee was incorrectly written and printed as "Edgar N. Miller," whereas said name should have been written and printed as *Edgar W. Miller*, as shown by the record of assignments in this office; and that the said Letters Patent should be read with these corrections therein that the same may conform to the record of the case in the Patent Office.

Signed and sealed this 9th day of March, A. D., 1920.

[SEAL.]

M. H. COULSTON,
Acting Commissioner of Patents.
